(57) **CLAIM**

The ornamental design for a body of an electric stringed instrument, as shown and described.

DESCRIPTION

FIG. 1 is a perspective view of the rear and right side of a body of an electric stringed instrument showing my new design; FIG. 2 is a perspective view of the front, bottom and right side thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof;

FIG. 9 is a cross sectional view at 9-9 line shown in FIG. 3; and,

FIG. 10 is a reference view of usage thereof.

The broken line showing of the body of the electric stringed instrument is included for the purpose of illustrating portions of the body of the electric stringed instrument and forms no part of the claimed design.
